CLAIM

The ornamental design for a fluid system and flashback creator for IV training as shown and described.

DESCRIPTION

FIG. 1 is a front, right and top perspective view of a fluid system and flashback creator for IV training showing my new design with corks detached and attached pushrods; FIG. 2 is a rear, left and bottom perspective view thereof; FIG. 3 is a front elevational view thereof; FIG. 4 is a rear elevational view thereof; FIG. 5 is a left view thereof; FIG. 6 is a right view thereof; FIG. 7 is a top plan view thereof; FIG. 8 is a bottom plan view thereof; FIG. 9 is a front, right and top perspective view of the fluid system and flashback creator for IV training with corks attached and push rods detached; and, FIG. 10 is a front, right and top perspective view of the fluid system and flashback creator for IV training with both corks and push rods detached.

The broken lines illustrate portions of the fluid system and flashback creator for IV training that form no part of the claimed design.

1 Claim, 10 Drawing Sheets
